UNITED STATES PATENT OFFICE.

GEORGE F. OTT, OF PHILADELPHIA, PENNSYLVANIA.

PRESSURE-REGULATOR.

SPECIFICATION forming part of Letters Patent No. 336,584, dated February 23, 1886.

Application filed December 23, 1885. Serial No. 186,521. (No model.)

To all whom it may concern:

Be it known that I, GEORGE F. OTT, a citizen of the United States, residing at Philadelphia, in the county of Philadelphia and State of Pennsylvania, have invented certain new and useful Improvements in Pressure-Regulators; and I do hereby declare the following to be a full, clear, and exact description of the invention, such as will enable others skilled in the art to which it appertains to make and use the same.

My invention consists of a governor which operates by variations of force between a weight or spring and a suspended flask partly filled with liquid flowing into it from an independent fixed vessel, the level or pressure of the liquid in which is subject to changes.

In order that my invention may be clearly understood, I have illustrated various forms and applications thereof in the annexed drawings, and will proceed to describe these forms successively.

Form 1, represented by Figure 1 of the drawings, illustrates the application of my invention for governing a steam-pump for feeding a boiler. A refers to the boiler, and B to the steam-feed pump thereof. The steam-chest of the pump receives steam from the boiler through a pipe, C, which contains the throttle-valve D. A lever, E, is fixed on the stem of the throttle-valve. One end of the lever carries a weight, e, and the other end carries the closed flask F. The top of the flask is connected by a flexible pipe or hose, f, with steam-pipe C at a point between the boiler and the throttle-valve, while the bottom of the flask is connected by a flexible pipe or hose, f', with the water-space of the boiler. The flask is hung at such height that when the water stands at the proper level in the boiler the weight will overbalance the flask and hold the throttle-valve open; but when the water in the boiler rises above this level, and consequently rises in the flask also, the weight of the flask will soon overbalance the weight e, close the throttle-valve, and hold it closed until the water in the boiler and flask sink so low that the flask is again overbalanced by weight e, when the throttle-valve is reopened.

Form 2, represented by Fig. 2 of the draw-

ings, illustrates the application of my invention for controlling the belt-shifter of a boiler-feed pump operated by belt-gearing. The flask F is suspended by a cord, f², which passes over a pulley, f³, on the supporting-frame G of the belt-shifter H, and is secured to the belt-shifter. A spring, I, acts on the belt-shifter antagonistically to the flask. When the flask sinks in consequence of a rise of water in it, the belt-shifter shifts the belt K from the fast pulley l on the crank-shaft L of the pump to the loose pulley l' thereon.

Form 3, represented by Fig. 3 of the drawings, illustrates the application of my invention for governing the supply of water by a steam-pump to a tank. A bulb, M, is connected by a pipe with the bottom of the tank N, and is partly filled with mercury, which flows through a flexible pipe, m, into the bottom of an open flask, O, suspended from one arm of a lever, P, the other arm of which is connected by a cord, p, with an arm, d, fixed on the stem of the throttle-valve D of steam-pump B, and carrying a weight, d'. When the water in the tank reaches the proper height, so much mercury will have been forced over from bulb M into flask O that the latter overbalances weight d', so as to close the throttle-valve D. If water is drawn from the tank, part of the mercury will flow back into the bulb from the flask, reducing the weight of the latter, so that weight d' will reopen the throttle-valve.

Form 4, represented by Fig. 4 of the drawings, illustrates the application of my invention for governing the supply of a liquid from an elevated tank to a basin or receiver at a lower level. The elevated tank N supplies the basin Q by a pipe, R, a valve, S, in which is controlled by the antagonistic forces of a weight, s', and a closed flask, T, connected, respectively, to the opposite arms of a lever, s, fixed on the valve-stem. The flask is connected by a flexible pipe with the bottom of basin Q. As the water in the basin rises, more and more water is forced in the flask, gradually compressing the air therein, until, when the basin has been filled to the proper height, so much water has been forced into the flask that it will overbalance the weight s' and close the valve S. If the water in the

basin sinks, the compressed air in the flask will force water out of it, so that the weight *s'* will reopen the valve.

Form 5, represented by Fig. 5 of the drawings, illustrates the application of my invention for governing the pressure of a liquid in a pipe, the governor controlling the induction-valve to the pipe in the manner clearly illustrated.

10 It will be observed that some applications of the invention demand a closed flask, while on other occasions an open flask may be used. The device on which the weight or spring and the flask act antagonistically, whatever its 15 specific character, is always a shifter generically; hence, under the term, "shifter," used in the ensuing claim, I include a lever for open-

ing and closing a valve, as well as a belt-shifter and other equivalent shifting devices.

I claim as my invention—

20 The combination, substantially as before set forth, with a shifter, of a weight (or spring) and a suspended flask acting antagonistically on the shifter, the said flask being partly filled with a liquid flowing into it from an independent fixed vessel, the level (or pressure) of the liquid in which is subject to changes.

25 In testimony whereof I affix my signature in presence of two witnesses.

GEORGE F. OTT.

Witnesses:

E. F. OTT,

WILLIAM S. TOLAND.
